UNITED STATES PATENT OFFICE.

ALFRED KUNZEL AND GEORG BRÄUER, OF HAMBURG, GERMANY.

SKIVING MACHINE.

Application filed November 3, 1921. Serial No. 512,670.

To all whom it may concern:

Be it known that we, ALFRED KUNZEL and GEORG BRÄUER, citizens of Germany, residing at Hamburg, in the Province of Altona 5 and Republic of Germany, have invented certain new and useful Improvements in Skiving Machines, of which the following is a specification.

The principal purpose of this invention is 10 to produce a machine for skiving leather vamps, as used in the construction of shoes, in a novel and rapid manner, whereby duplicates are produced automatically by mechanical means.

15 A further object is the production of a machine upon which the blanks are successively manually applied, operated upon by an adjustable, rotative knife and finally ejected in a finished condition, with a minimum of hand labor.

20 Another object is to provide means for securely clamping the blank closely adjacent to the edge of the cutter during its operation, other means operating to advance the blank positively during its travel contiguous to the cutter.

25 These and kindred objects are attained by the novel construction, combination and arrangement of parts hereinafter described, and shown in the accompanying drawings, 30 forming a material part of this disclosure and in which:—

Figure 1 is a vertical sectional view of a machine made in accordance with the invention, the section being taken on line 1—1 of Fig. 3.

Figure 2 is a transverse sectional view taken on line 2—2 of Fig. 1.

Figure 3 is a plan view of the machine, the 40 knife, its driving means and support being omitted.

Figure 4 is a fragmentary vertical sectional view taken on line 4—4 of Fig. 3.

Figure 5 is an enlarged partial view of 45 the same showing the blank ejecting means in a raised position, the view being taken in a slightly different plane from that of Fig. 4.

Figure 6 is a fragmentary front view of 50 the same.

Figure 7 is a fragmentary sectional view, taken substantially on line 7—7 of Fig. 3 and showing the mounting of the pressure feed roller.

55 Stated briefly in general terms, the invention comprises a rigid stand on the top

of which is mounted a flat ring having peripheral teeth by which it is rotated, the ring being held to the stand by a clamp 60 engaging an annular flange at its inner diameter.

Blank holders are arranged in series on the face of the ring; each having a recess receptive of a single blank, these holders 65 passing under a conical, corrugated roller, driven by gears from the ring and being flexibly mounted so as to be raised and lowered by cams.

A plain roller is similarly mounted adjacent and in addition to its vertical movement is caused to move radially following the outline of the blank.

A disc cutter is used, the same having a bevelled edge and is supported adjustably 70 of the stand on a slightly inclined axis.

75 As the work holders are advanced means are provided to knock out a skived blank so that feeding untreated blanks is only required, the machine being driven by power 80 as shown.

85 Referring to the drawings in detail, the numeral 15 designates the base of a stand curved convergently to about the center of its height, the contracted portion 16 expanding into a top plate 17, having at the front a concentrically curved extension 18 from which extends a bracket foot 19 level with the center 20.

90 A pair of brackets 23, extend up from the flanged base 15, in which are mounted a shaft 24 carrying a driven pulley 25 and a pair of driving pulleys 26 and 27.

95 A pair of plate brackets 28 extend rearwardly from the portion 16 of the stand, mounting spindles 29 on which are idle wheels 30 and 31 guiding a belt 32 from the larger driving pulley through openings 33 and 34 in the frame to a drive pulley 35 fixed on a vertical shaft 36.

100 This shaft 36 is mounted in a step bearing 37 extending outward at the front of the stand, is further guided by passing through a bearing 38 in the extension 18 and is finally housed in a bearing 39 formed in a frame 40, one element 41 of which is secured on the 105 foot bracket 19 and the other 42 on the stand center 20 as shown in Fig. 1.

110 An arm 44 extends inwardly of the frame 40 and the cutter spindle 45 is journaled in it, the upper end of the spindle being housed in an adjustable thrust bearing 46 carried by the frame 40, this spindle being slightly in-

clined so that the cutting edge of the disc or revolving knife 47 is presented in an inclined plane relative to the surface of the stand, the advance edge being the lowermost.

5 A relatively wide faced spur gear 48 is fixed on the cutter spindle 45, meshing with a driving gear 49 secured on the shaft 36, thus conveying rotary motion to the cutter.

An offset arm 50 extends from the stand 10 portion 16, the arm terminating in an elongated bearing 51, mounting the shaft 52, this shaft having attached at its inner end a pulley 53 driven by a belt 54 from the pulley 26.

15 The outer end of the shaft 52 has fixed to it a cone 55 over the steps of which may be trained a belt 56 leading to a similar reversed cone 57 fixed on a horizontal shaft 58, housed partially in a bearing 59 extending 20 from the top of the stand, and a pair of lug extensions 60 also formed with the stand at the rear near the top.

Fixed to the shaft 58, between the lugs 60 is a worm or helix 61 used to drive the turn 25 table 62, the latter being fitted to rotate within an annular recess in the top of the stand, circumjacent the center 20 and held in position by a ring 63 loosely clamped to the stand.

30 It will be understood that the turn table is provided with peripheral teeth, engaging the worm 61 and, as shown, clearance recesses 64 and 65 are formed respectively in the adjacent surfaces of the turn-table and 35 stand top.

A plurality of segmental work holders 68, four being shown, are secured to the turn-table by screws or like fastenings, in each 40 of which is a central depression 70, deepest at their curved outer edge 71 and inclined upward at their front edges 72 and ends, the curve of their outer profile being of smaller radius than the inner.

45 All of the edges are smoothly rounded and finished as they receive the leather blanks when in a softened condition, the shape of the recesses being transferred to the blanks in the manner of a die or mould.

Immediately adjacent the advance edge of 50 the cutter 47 is a radially disposed shaft 75, its inner end being mounted in a bracket 76 adjustably secured to the stand center 20, and its outer end in a similar bracket 77 fixed on the extension 18.

55 Secured to the shaft 75 is a spur pinion 78 meshing with a circular rack 80 extending up from the turn-table 62 near its inner periphery, as best shown in Fig. 3.

Fixed to the shaft 75 near its outer end 60 is a roller 81 adapted to engage the inclined face 82 of raising cams 83, which are arcuately formed and secured near the outer peripheries of the segments 68.

The outer portion of the cam 83, over 65 which the roller 81 travels terminates ab-

ruptly while the inner portion 84 continues in length about one third of the length of the depressions 70, both portions attaining their full height at points coincident with the advancing ends of the depressions.

70 A pair of bearings 86 and 87 similarly to the bearings 76 and 77 are mounted in a like manner rearwardly on the stand and carry a shaft 85.

All of these several bearings contain slotted openings receptive of the shafts and permitting them to rise, due to the action of the cams, against the pressure of spring 88 set in cups 89 and controlled by screws 90 as shown best in Fig. 7, the spring forcing 80 the shafts downward to the bottoms of the slots 91 as soon as the rollers have passed the cams.

The roller 92 is fixed to the shaft 85 at the end of a conical roller 94, its base or 85 largest diameter being outward, and its surface corrugated or roughened as shown to tightly engage the leather blanks as they are passed below. The shaft 85 is driven by a spur pinion 95 meshing with the circular 90 rack 80.

It is noted that the roller 92 is closer to the center of the stand than the roller 81 and, therefore, after being raised by the inclined surfaces 82, travels over the cam 83, 95 holding the shaft 85 and corrugated roller out of contact with the work a greater interval of time.

Slidable on the shaft 75 is a sleeve 97 extending from a narrow smooth faced roller 100 98 pressed normally outward by an encircling compression spring 99, and fixed to the outer end of the sleeve 97 is a disc 100, the disc, sleeve and roller 98 acting as a unit.

The disc 100 is caused to slide along the 105 shaft 75, towards the center of the stand, by means of cams 101 formed with the segments 68, these cams being adapted to cause the roller 98 to follow a path indicated by the inner edge 72 of the work holding recesses, clamping the blanks in the recess immediately adjacent the cutting edge of the revolving knife 47.

When this operation has been performed and the turn-table has carried the parts 115 from under the knife, the blanks being skived and formed, are now ejected which is accomplished as follows:—

In the center of each recess 70 is an opening receptive of a plunger 105 having an 120 enlarged head held normally level in the bottom of the recess by a coiled spring 106.

Carried in a projection of the stand is a sliding plunger 107 having an annular groove 108 and pressed normally upward by a 125 coiled compression spring 109 surrounding the stem 110 of the plunger.

The lower end of the stem is threaded right hand and connected by a coupling 111 with a stem 112 having a left hand thread 130

and held rigid in a fork 113 in which are two fixed pins 114.

Formed on the peripheral edge of the segments 68 are extending cams 115 the drop 5 of which is substantially in a plane with the radial center of the depression 70.

Passing through the stand extension 18 are two radial slots, respectively 116 and 118, through the former of which extends a 10 lever 117, pivoted on an arm 119, extending from the stand and having attached to it a rod 120, pressed normally towards the plunger 107, by a spring 121, so as to enter the recess 108 and retain the plunger when 15 in a retracted position until released by the cam.

When so released the plunger 107 is forced up, making contact with the end of the plunger 105, causing it to rise and expel the 20 blank from the recess, the plungers being in alignment during that movement.

Another lever 125 is pivoted in the slot 118 so as to be actuated by the cams 115 as they pass and connected with the lower end 25 of the lever, by a link 126, is a curved lever 127, its bent end 128 extending between the pins 114 of the fork in such manner as to exert a pull on the same, retracting the plunger 107, whereupon the detent 120 enters 30 the recess and holds it until again released.

In operation, the softened blanks are placed over or partially in the recesses as the machine operates and as the table revolves are pressed firmly by the roller 94 and 35 held in position for the cutting operation of the knife 47 in a manner which will be readily understood.

The continuous further advancement of the machine carries the skived blanks beyond 40 the cutter and expels the same automatically as described.

Having thus described our invention, what we claim as new and desire to secure by Letters Patent, is:—

45 1. A skiving machine comprising a stand, a segmentally sectional turn-table rotatable on said stand, each section having a work blank receiving recess, a rotary knife above said turn-table, a corrugated conical roller mounted radially on said stand over the turn-table adapted to impinge upon the work blanks adjacent said knife, and means for periodically raising said roller during the entrance of a blank thereunder.

55 2. A skiving machine comprising a stand, a segmentally sectional turn-table rotatable on said stand, each section having a work blank receiving recess, a rotary knife above said turn-table, a corrugated conical roller mounted radially on said stand over the turn-table adapted to impinge upon the work

blanks adjacent said knife, cams on said turn-table adapted to raise said roller at fixed intervals, and means on said turn-table for rotating said roller. 65

3. A skiving machine comprising a stand, a segmentally sectional turn-table rotatable on said stand, each section having a work blank receiving recess, means for continuously actuating said turn-table, a rotary 70 knife supported above said turn-table, a clamp roller journaled on said stand bridging said turn-table adjacent the knife and means for raising said roller coincidentally with the entrance of a blank therebelow. 75

4. A skiving machine comprising a stand, a segmentally sectional turn-table rotatable on said stand, each section having a work blank receiving recess, means for continuously actuating said turn-table, a rotary knife supported above said turn-table, a clamp roller journaled on said stand bridging said turn-table adjacent the knife and means for raising said roller coincidentally with the entrance of a blank therebelow, and means 80 for moving said roller transversely of said turn-table to follow the outline of a work blank thereon. 85

5. A skiving machine comprising a stand, a turn-table mounted thereon, a rotary knife disposed over said turn-table, a pressure roller mounted adjacent said knife, means for moving said roller transversely over the face of said turn-table, a corrugated roller disposed radially rearward of said pressure 90 roller, means for rotating the rollers simultaneously, and means for raising said rollers in sequence at the entrance of work blanks 95 therebelow.

6. A skiving machine comprising a stand, a turn-table mounted thereon, a rotary knife disposed over said turn-table, shafts on said stand bridging said turn-table, bearings for said shafts permitting upward movement, means for rotating said shafts, pressure rollers on said shafts impinging on said turn-table and means for periodically raising said 100 shafts. 105

7. A skiving machine comprising a rotary table having work receiving recesses, means 110 for clamping blanks in the recesses, a rotary cutter for trimming the blanks, a spring actuated knock-out at the bottoms of the recesses, said knock-out being held normally retracted, a plunger for actuating said 115 knock-out, cams for releasing said plunger, a spring for actuating said plunger, and cam actuated means for retracting said plunger.

In witness whereof we affix our signatures.

ALFRED KUNZEL.
GEORG BRÄUER.
